MICROPHONE OR THE LIKE

Eliot F. Noyes, New Canaan, Conn., assignor to International Business Machines Corporation, Armonk, N.Y., a corporation of New York

Filed Dec. 7, 1967, Ser. No. 9,685

Term of patent 14 years

(Cl. D26—14)

FIG. 1 is a front perspective view of a microphone or the like illustrating my new design;

FIG. 2 is a top plan view thereof;

FIG. 3 is a front view thereof;

FIG. 4 is a rear perspective view thereof; and

FIG. 5 is a right side elevation thereof.

The dominant features of my design reside in the portions shown in full lines.

I claim:

The ornamental design for a microphone or the like, substantially as shown and described.
